DESIGN FOR A TILE UNIT OR ANALOGOUS ARTICLE

Albert A. Richards, Montebello, Calif.

Application February 25, 1939, Serial No. 83,567

Term of patent 14 years

To all whom it may concern:

Be it known that Albert A. Richards, a citizen of the United States of America, residing at Montebello, in the county of Los Angeles and State of California, has invented a new, original, and ornamental Design for a Tile Unit or Analogous Article, of which the following is a specification, reference being had to the accompanying drawing, forming a part thereof.

I claim:

The ornamental design for a tile unit or analogous article, substantially as shown.

ALBERT A. RICHARDS.
